UNITED STATES PATENT OFFICE.

RISDON DENT MOORE, OF ARDMORE, OKLAHOMA.

CAR-DOOR-SEALING DEVICE.

1,113,040.

Specification of Letters Patent.

Patented Oct. 6, 1914.

Application filed November 9, 1912. Serial No. 730,375.

To all whom it may concern:

Be it known that I, RISDON D. MOORE, of Ardmore, in the county of Carter and State of Oklahoma, have invented certain new and useful Improvements in Car-Door-Sealing Devices; and I hereby declare that the following is a full, clear, and exact description thereof, reference being had to the accompanying drawings, which form part of this specification.

This invention is a novel improvement in railway cars and its object is to provide novel means for tightly sealing the car doors so as to protect the contents of the car from damage by rain, dirt, fire, etc., which might enter from the outside of the car; and also to effectively retain any fine materials in the car.

Another object of the invention is to provide such a sealing device which can be applied to an ordinary freight car door with very little expense.

I will explain the invention in detail in connection with the accompanying drawings which illustrate one embodiment of the invention applied to an ordinary freight car door, and which will suffice to impart a clear understanding of the nature and object of the invention and the essential features thereof, and a practical means of utilizing same.

In said drawings—Figure 1 is a front view of a freight car door equipped with my novel sealing device; showing the devices in retracted position in full lines. Fig. 2 is a detail view of the sealing devices in sealing position. Fig. 3 is an enlarged detail section on line 4—4, Fig. 2.

I have illustrated the invention as applied to an ordinary wooden box car door which may be of any suitable construction, and is shown as suspended by hangers 1^a from a bar 1^b extending above the top edge of the door opening, the hangers being such that the door may be swung slightly outward from the door frame and then moved edge-wise to one side of the door opening, along the side of the car in the well known manner.

Mounted on the door adjacent the edges thereof which it is desired to seal, are sealing plates 2, each of which lies preferably against the outer face of the door, adjacent an edge thereof; and preferably four such plates are employed respectively at the top,

bottom and front and rear edges of the door. These plates are preferably made of sheet steel and laterally movable, and are fastened to the door by suitable means, as by bolts 2^b engaging transverse slots 2^a in the plates as shown. The bolts and slots allow the plates to be moved laterally toward and from the edges of the door, and at the same time hold them securely thereto. Any other suitable means for holding the plates in this manner can be used.

The plates may be simultaneously moved inwardly or outwardly by suitable means. As shown a disk 3 is pivotally mounted upon a stud or bolt 3^a attached to the outer face of the door and preferably at the center thereof; this disk may be wheel-shaped for lightness and is provided with a radially projecting arm 3^b by which it can be turned. Connected to this disk at points 90° apart are links 4 which may be bifurcated at their outer ends, and the extremities of the bifurcations 4^a pivoted to the several plates 2, as indicated at 4^b; the construction is such that when the disk 3 is turned in one direction all the plates 2 will be simultaneously retracted or drawn inwardly toward the disk, and if the disk is turned in the opposite direction the plates will be simultaneously projected or moved outward away from the disk.

The plates may be held in projected position by fastening the arm 3^b in any suitable way, as by engaging the arm 3^b with a retainer 5 having a hinged upper piece 5^a which can be locked after the arm is engaged therewith, as indicated in Fig. 1 of the drawings.

At the edges of the door opening, or opposite each plate 2 on the door, may be metal plates 6, which will not interfere with the seating of the door in its place when the plates 2 are retracted.

As shown loops 7 are attached to the car adjacent the door opening, and the bifurcations 4^a project beyond the outer edges of the plates 2 and are provided with wedge shaped ends 4^c adapted to engage the loops 7, when the door is closed in place and the links 4 projected, so as to force the plates 2 closely against the outer sides of the door frame, as indicated in Figs. 2 and 3, thus sealing the edges of the door.

It will be seen that by this invention I close or seal the cracks at or around the

edges of the door; and such sealing devices can be applied to any ordinary form of car door.

What I claim is:

5. 1. In combination with a car door, laterally movable plates attached to the door adjacent each edge thereof, a pivoted lever, links on the same side of the door as said movable plates connecting said lever with each of the plates and having their outer ends extended beyond the said plates, said links being adapted to simultaneously project or retract the plates when the lever is rocked, and devices attached to the car adjacent the door opening adapted to be engaged by said projecting ends of the links, said ends and devices being so relatively formed as to press the plates closely against the door frame and door at the meeting edges thereof when the links are projected, substantially as described.
- 10 20. 2. In combination with a freight car door,

laterally movable plates attached to the door adjacent each edge thereof, a lever pivoted on the door, and links on the same side of the door as said movable plates connecting said lever with each plate to simultaneously project or retract the latter when the lever is rocked, said links having wedge-shaped ends extended beyond the plates; with devices attached to the door frame adjacent the door and opposite each lever end and adapted to be engaged by the wedge-shaped ends of the levers and press the plates closely against the door frame and door at the meeting edges thereof when the links are projected, substantially as described.

In testimony that I claim the foregoing as my own, I affix my signature in presence of two witnesses.

RISDON DENT MOORE.
